UNITED STATES PATENT OFFICE.

POWELL EVANS, OF PHILADELPHIA, PENNSYLVANIA, ASSIGNOR TO INTERNATIONAL SPRINKLER COMPANY, OF PHILADELPHIA, PENNSYLVANIA, A CORPORATION OF PENNSYLVANIA.

DRY-PIPE VALVE.

SPECIFICATION forming part of Letters Patent No. 731,877, dated June 23, 1903.

Application filed November 24, 1902. Serial No. 132,629. (No model.)

To all whom it may concern:

Be it known that I, POWELL EVANS, a citizen of the United States, residing in Philadelphia, Pennsylvania, have invented certain improvements in Dry-Pipe Valves, of which the following is a specification.

My invention relates to improvements in fire-extinguishing apparatus; and it consists in a dry-pipe valve of novel and advantageous construction, being more particularly an improvement on the device for which Letters Patent of the United States No. 695,294 were granted to me on March 12, 1902.

The objects of the present invention are to improve the detail construction as well as to provide means for increasing the reliability and certainty of action of my above-mentioned valve. These objects I attain as hereinafter set forth, reference being had to the accompanying drawings, in which—

Figure 1 is a sectional elevation of my improved dry-pipe valve, showing its parts in the positions occupied when air-pressure in one part of the system operates through mechanism hereinafter described to prevent the flow of water from another section of the system to said first section. Fig. 2 is a side elevation of my improved valve, a portion of the inclosing casing for the mechanism being removed; and Figs. 3 and 4 are sectional plan views taken on the lines 3-3 and 4-4, Fig. 1, respectively.

In the above drawings, A is a valve-casing forming part of the main water-supply pipe of a dry-pipe fire-extinguishing system, this casing having an inlet a and an outlet a' for water and an opening a² provided with a valve-seat a³ for the passage of the mechanism connecting the air and water valves, in addition to which there is a main drip-opening a⁴ and other openings closed by plates a⁵ and a⁶, through which access may be had to the intermediate chamber of the casing and to the top of the air-valve.

Within the casing are fitted a diaphragm B and a valve-seat C, for which there are provided valves b and c, respectively, these latter serving under normal conditions to prevent access of both air and water under pressure to the portion of the casing included between

them and known as the "intermediate" chamber of said casing.

I preferably retain the diaphragm B in operative position by confining it between the flange of a fitting A' and a suitable face on the casing A, the said fitting opening in any desired or convenient direction and the diaphragm serving as a yielding seat for the valve b.

The valve c is pinned to an arm c³ by means of a bolt c⁴, said arm being hinged to the interior of the valve-casing by means of a pivot-pin c'. A piece of spring-bronze c⁵, extending around the arm c³, is held in place by the bolt c⁴ and serves as a buffer for the valve when this latter is violently swung on its pivot or hinge when operating to permit the passage of water. The valve b is also hinged or pivotally supported by means of a strut D, hereinafter referred to as the "fork," pinned at d to a casting E, upon which the casing A is preferably supported.

The opening a², with its seat a³, is so placed in the casing A with respect to the valve B and the pivotal support d that the valve b may under certain conditions of operation seat itself upon said seat-ring, so as to close the opening therethrough.

The two valves b and c are operatively connected by means of a system of struts and levers consisting of the fork D, the lever F, a weighted lever G, a lever H, hereinafter called the "tumbler," and a strut I. The fork D is engaged when the various parts of the device are in the positions shown in Fig. 1 by the lever F, which in turn is carried upon a bolt or pin f', passing between two lugs or projections a⁷, preferably formed integral with the casing A. The free end of said lever F is of such a length as to engage a bearing-surface at g upon the weighted lever G, the distinctive feature of the latter lever being that one of its arms has attached to or formed integral with it a relatively heavy weight g', the lever as a whole being provided with a bearing or support e, formed in suitable lugs e², projecting from the supporting part or standard E. A link or bar J is pivoted to the lever F near its lower end and is provided with an elongated slot j, through which

passes a pin g^2 , serving to movably connect it to the weighted lever G.

The tumbler H has a knife-edge support h and is so constructed that one of its arms h' engages a cross-piece g^3 of the lever G, its other arm h^2 being provided with an elongated depression or slot for the reception of the wedge-shaped end of the strut I. This construction is employed in order to prevent the possible rotation of said strut which might bring some part of it into contact with the fork. The fork D is slotted or made in open form, as shown in Fig. 2, to permit of the passage through it of the second strut I, whose upper end is rounded to fit within a depression or recess in a lug c^2 , projecting downwardly from the under side of the valve c, said strut also having a projecting portion or lug i , provided with an elongated slot i' for the reception of a pin d' ; by which the strut is held to the strut D, while being free to move relatively to the same.

An external shell or casing fits around and incloses all of the above-described mechanism which projects outside of the main valve-casing A, this casing being formed in two parts K and K' and provided with lugs k , by which said parts are secured to and supported by the portion E of the device.

As shown in Figs. 2 to 4, one portion of the inclosing casing has a flange k' overlapping the edge of the other, the bottom edges of the parts being slightly separated and sloping to a vertical plane, so that the casing cannot be closed with any object left within it which might interfere with the operation of the valve mechanism. There is below this inclosing casing a suitably-formed receptacle e^3 for the reception of water, this being in the present instance integral with the supporting-section E and provided with an opening e' in its bottom for the escape of such water. The two sections of the casing are held together by a bolt k^2 , which passes through suitable lugs in said sections.

Under normal conditions the various parts of the apparatus are in the positions shown in Fig. 1, the air under pressure in the sprinkler system in connection with the opening a' of the casing pressing against the valve c and holding it closed against water under a much higher pressure from a water-supply system against the valve and transmitted through the levers and struts D, F, G, H, and I.

It is to be understood that the end of the strut D is seated in a depression in the transverse portion f^2 of the lever F, the strut being of such length that when the mechanism is in its "set" position the valve b is pressed against its diaphragm sufficiently to move it outwardly, as indicated in the drawings. The tightness of the closure thus effected by the valve b is still further assisted by the water-pressure within the portion of the system connected to the inlet a which acts upon the diaphragm, so as to press it with a relatively large pressure upon the narrow valve-

face. When, however, the air-pressure in the sprinkler system falls below a predetermined point, the valve c rises, thereby permitting motion of the strut I and of the tumbler-lever H, such action being materially assisted by the lever G, whose weighted arm g' always tends to revolve said lever H upon its supporting knife-edge h . The turning of the weighted lever G upon its supporting member e permits the downward swing of the long arm of the lever F and allows the valve b to seat itself upon the ring a^3 , the water under pressure then flowing from the inlet a past diaphragm B, the valve-seat C, and into the sprinkler system connected to the outlet a' . Violent or excessive motion of the long arm of the lever F is prevented by the link J, which, being attached to the weighted portion g' of the lever G, restrains such action and makes possible the relatively small casing, as shown. It is thus seen that the weighted arm of the lever G has a number of functions, for not only does it exercise a constant force tending to open the valve c, but as it turns on its pivot or falls it pulls the long arm of the lever F through the link J and then checks excessive movement of said lever F by the same means.

It will be understood that during the passage of water through the valve-casing the valve b remains seated upon the ring a^3 , thus preventing the escape of water, while the valve c assumes a substantially perpendicular position at one side of the upper portion of the casing A, being cushioned when swung upwardly by means of the spring-piece c^5 . After the flow of water through the valve-casing has been stopped by the shutting of a valve suitably placed in the supply system the remaining water may be drained off through the conduit a^4 , the valve c returning to its seat under the action of gravity. Upon the air-pressure being again admitted to the sprinkler system, so as to exert pressure upon the upper surface of said valve c, the valve b is raised from the ring a^3 and the various levers and struts set in position as shown in Fig. 1, any surplus water draining off through the opening e' . Water under pressure is then admitted to the supply system, so as to press against the valve b, and the device is again in condition for operation.

As above set forth, the peculiar construction of the diaphragm B and valve b insures a perfectly water-tight closure, thereby rendering possible the omission of the adjusting-bolt ordinarily carried by the lever F and engaging the strut D. The yielding diaphragm takes up all lost motion between the various members while being forced against the valve by direct water-pressure. By reason of this advantageous construction an almost indefinite pressure can be brought to bear upon the valve b with but a relatively very slight downward push of the end of the long arm of the lever F upon the arm-lever G. At the same time it will be noted that by the

use of a weight, as g' , placed to act through its connecting-levers upon the valve c the pressure at which said valve will open and cause the opening of the valve d may be calculated within exceedingly small limits and the operation of the device rendered correspondingly capable of close adjustment to suit any desired conditions. As a result of this arrangement of parts the air-valve c can be 5 and in practice is designed to open when the air-pressure in the sprinkler system varies between very small limits, and yet the valve b may press so tightly upon its seat that there is no possibility of a leakage of the water acting 10 against it.

I preferably form the cup-shaped cavity in the lower face of the lug c^2 of the valve c of such dimensions that when the lower end of the strut I is placed in engagement with its 15 arm of the tumbler it shall not be possible for the upper end of said strut to avoid entrance into said cavity, since any tendency of the strut to pass the lug c^2 when the device is being set would be prevented by contact with the pin d' , the proper seating or engagement of the upper end of said strut in the cavity being thus assured. Similarly the receiving-slot in tumbler H is guarded on its sides, so 20 that the lower end of strut I must assume its proper position and without the possibility of incorrect sitting.

I claim as my invention—

1. The combination in a valve structure designed to form part of the main conduit of a 35 dry-pipe fire-extinguishing system, of a casing containing two main valves, mechanism operatively connecting said main valves whereby air-pressure on one valve is caused to prevent motion of the other valve from 40 fluid-pressure acting thereagainst, said mechanism including a plurality of levers, one of the same being provided with an enlarged portion forming a weighted arm placed so that it tends to open the air-valve, substantially as described.

2. The combination in a dry-pipe valve, of a casing, valves therein having connecting mechanism whereby air-pressure on one valve acts to prevent motion of the other valve 50 from water-pressure acting against it, said mechanism including two levers having arms in engagement with one another, one of said arms being weighted, and a link connecting said weighted arm with the arm of the other lever, substantially as described.

3. The combination in a dry-pipe valve, of a casing, valves therein having connecting mechanism whereby air-pressure on one valve acts to prevent motion of the other valve 55 from water-pressure acting against it, said mechanism including two levers having arms in engagement with one another, one of said arms being weighted, and a link connecting the end of said weighted arm with the end of the arm of the other lever, substantially as described.

4. The combination in a dry-pipe valve, of

a casing, valves therein for controlling the flow of fluid through the casing, mechanism connecting the valves, said mechanism including three levers, two of said levers each having an arm in engagement with the third lever, said third lever having a weighted portion, and a link connecting said weighted portion with one of the arms of said first two levers, substantially as described.

5. The combination in a dry-pipe valve of a casing having two valves for governing the flow of fluid therethrough, mechanism connecting the valves, said mechanism including 70 a series of levers, a casing outside of said dry-pipe valve inclosing said mechanism, and means for permanently connecting certain arms of the levers together whereby undue motion of said arms is prevented, substantially as described.

6. The combination in a dry-pipe valve, of a casing, valves therein for controlling the flow of fluid through the casing, mechanism connecting the valves, said mechanism including a strut in engagement with each valve, a lever in engagement with the free end of each strut, a third lever having an arm in detachable engagement with an arm of each of said levers, with means for permanently 90 connecting said third lever to a portion of the mechanism connecting the valves, substantially as described.

7. In a dry-pipe valve, the combination of a casing, valves therein for controlling the flow of fluid, mechanism connecting the valves whereby pressure upon one valve acts to prevent motion of the other, said mechanism including a strut designed to engage one of the valves and levers connecting said strut to the other valve, with means for limiting the motion of said strut relatively to its valve, one of the members comprised by the strut and the valve having an extended portion of dimensions bearing a predetermined relation 100 to said motion-limiting means, whereby operative engagement of said strut with its valve is insured when the remainder of the mechanism is being placed in its set position, substantially as described.

8. In a dry-pipe valve, the combination of a casing, valves therein for controlling the flow of fluid, mechanism connecting the valves whereby pressure upon one valve acts to prevent motion of the other, one of the valves being provided with a lug having an extended portion, said mechanism including a strut designed to engage the extended portion of said lug and levers connecting said strut with the other valve, a portion of said 110 connecting mechanism having a device for compelling said strut to engage with the extended portion of the lug when the remainder of the mechanism is being placed in its set position, substantially as described.

9. In a dry-pipe valve, the combination of a casing, valves therein, mechanism connecting said valves whereby the pressure upon one of the same acts to prevent motion of the

other, a portion of said mechanism extending outside of the casing, a standard supporting the valve-casing and a shell extending around the external portion of said mechanism, said shell having an opening at the bottom and the standard having a portion extending under said opening for the reception of liquid escaping from the valve-casing, substantially as described.

10. In a dry-pipe valve, the combination of a casing having within it valves for controlling the flow of fluid therethrough, mechanism connecting said valves so that air-pressure upon one valve prevents motion of the other, said mechanism including struts engaging the valves, one valve having a projection for the reception of the end of its strut, said strut being loosely pinned to a portion of the mechanism in such manner as to limit its transverse motion to an extent sufficient to insure its engagement with the projection on the valve when said valve is closed and the other end of said strut is engaged by the appropriate portion of the mechanism, substantially as described.

11. In a dry-pipe valve, the combination of a casing having valves and mechanism connecting the same whereby one of the valves exposed to water-pressure is kept seated by air-pressure acting on the other valve, said mechanism including a system of levers and struts, one of the levers being operatively connected to a valve by one of the struts, said valve having a concave portion for the reception of said strut, said lever and the strut comprising elements of which one is provided with a wedge-shaped portion having its edge in a line substantially parallel to the axis of the pivot of said lever and the other element has a slot for the reception of said edge, with means engaging said strut to

limit its movement when the valve parts are being assembled for operation and thereby insure the engagement of one of its ends with the concave portion of the valve when the other end engages said lever, substantially as described.

12. In a dry-pipe valve, the combination of a casing constructed to form a part of the main conduit of a fire-extinguishing system and having within it valves for controlling the flow of fluid therethrough, mechanism connecting said valves so that air-pressure upon one valve prevents motion of the other, said mechanism including a system of struts and levers placed to connect certain members of the mechanism, one of said levers having a weight acting upon its arms placed to continually tend to open the air-valve in said main conduit independently of the pressure upon the water-valve, substantially as described.

13. The combination in a dry-pipe valve, of a casing containing valves, mechanism operatively connecting said valves whereby air-pressure on one valve acts to prevent motion of the other valve from water-pressure, said mechanism including a plurality of levers and a device tending to open the air-valve irrespective of the water-pressure, said device having means for positively moving one of the levers when the air-valve opens and means serving to limit the motion of said lever after such movement, substantially as described.

In testimony whereof I have signed my name to this specification in the presence of two subscribing witnesses.

POWELL EVANS.
